(57) **CLAIM**

The ornamental design for an absorbent article with a pattern, as shown and described.

DESCRIPTION

The sole FIGURE is a development view of an absorbent article with a pattern, showing our new design.

The broken lines, including those showing the diaper tabs and ears, are included for the purpose of illustrating environment and form no part of the claimed design.

The zig-zag lines on the absorbent article itself with the appearance of stitching form a part of the claimed design.
